UNITED STATES PATENT OFFICE.

EDGAR B. NICHOLS, OF ROCHESTER, NEW YORK, ASSIGNOR TO THE PFAUDLER CO., OF ROCHESTER, NEW YORK, A CORPORATION OF NEW YORK.

AGITATOR.

Application filed October 1, 1923. Serial No. 665,772.

This invention relates to agitators, and more particularly, to the rotary variety adapted for agitating the liquid contents of a container, one object of the invention being 5 to provide a practical agitator of this character which may be manufactured at a comparatively low cost with respect to materials and labor. A further object is to provide such an agitator efficiently constructed of 10 metal in such a manner as to be adapted to have a vitreous or enameled coating fused thereon. A further object of the invention is to provide an improved method of constructing hollow agitators from sheet material 15 to afford one having walls of substantially uniform thickness throughout with a coating of enamel applied thereto for protecting the same. Still a further object is the provision of a device of this nature economically 20 constructed of metal tubing and so designed as to be particularly adapted for the reception of a sanitary and durable fused vitreous coating. To these and other ends the invention consists in certain improvements and combinations of parts, all as will be hereinafter more fully described, the novel features being pointed out in the 25 claims at the end of the specification.

In the drawings:

- 30 Figure 1 is a side elevation of an agitator embodying the present invention;
Figure 2 is an end elevation thereof;
Figure 3 is an enlarged sectional view on the line 3^a—3^a of Figure 1;
35 Figure 4 is a sectional view on the line 4^a—4^a in Figure 3, and
Figure 5 is a sectional view on the line 5^a—5^a in Figure 3.

Similar reference numerals throughout the 40 several views indicate the same parts.

The embodiment of the invention herein disclosed by way of illustration of the principles involved comprises a rotary agitator of the centrifugal type although of course 45 the broader aspects of the novel principles embodied may be applied as well to other types of agitators. Devices of this character have been commonly manufactured of non-corrosive metal in solid form but this 50 practice is obviously wasteful of material where no great stresses are involved requiring maximum strength. Agitators have also been manufactured in this solid form of inexpensive metal and given a noncorrosive coating, but a coating material having 55

marked advantages, namely, vitreous material or glass enamel, involves objectionable difficulties in applying the same to an article of such solid construction because of the varying mass of the metal in its different 60 portions and consequent inequalities in temperature conditions with attendant liability to defects in the enamel coating, as well understood in the art.

It has been found that agitators of this 65 nature may be practically and economically manufactured as a hollow body formed by relatively thin metal walls and requiring comparatively little metal material. Such a mode of construction furthermore affords 70 a metal agitator particularly adapted for subjection to the process of fusing an enamel on its external surfaces.

In the present instance the agitator is constructed of standard tubing, a length of 75 which, as indicated at 10, forms an elongated hub portion for the agitator having a closed and preferably slightly projecting rounded end 11 and an open opposite end 12 adapted to receive a shaft. The projected rounded 80 end 11 is adapted to facilitate the flow of material and avoid the tendency to establish a region of reduced pressure at this portion. The hub portion is furthermore formed with lateral openings 13 of which in the present 85 instance there are four, spaced about its periphery adjacent the end 11 at which openings the blades are attached.

The blade portions also are preferably 90 formed of lengths of standard tubing as indicated at 14, one end of each such tube length being fixed to the hub around one of the openings 13, as for example by a welding, brazing or similar process. The outwardly extending portion of each blade is 95 elongated, or partially flattened, transversely of the plane of rotation as at 15 (Figure 3) and as shown in Figure 4. The blade is also curved substantially spirally in the 100 plane of rotation for the purpose of securing the most efficient propelling effects as well understood in the art. The outer ends of the blades are closed by rolling the margins at this end toward each other as at 16 and welding, brazing or otherwise uniting 105 the same as indicated by the heavy line in Figure 5. These blade portions may be readily drawn by usual operations into the present and various other suitable forms at a comparatively low cost, and the above 110

construction may be given the desired strength by the selection of tubing of suitable thickness.

An agitator may be constructed as above described of tubing of noncorrosive metal with satisfactory results, but it is preferred to utilize with such construction a coating of vitreous material, as indicated on an exaggerated scale at 17, Figure 5, because of the well known durability and other qualities of the same. In this case steel tubing may be employed as already stated, and it is to be noted that the construction is such that all portions of the agitator are of substantially equal thickness or mass of metal and all portions of the interior are in free communication with each other and with the exterior through the shaft opening of the hub, as is desirable for equalizing temperature conditions as well as the pressures of gases which may be generated interiorly during the heating process by which glass or other vitreous material is fused or baked on the external surfaces.

The invention supplies therefore a light but strong article having an integral form of construction which may be produced by practical manufacturing methods at a comparatively low cost, and which is furthermore particularly adapted for the application thereto of a protective coating of vitreous material having the various qualities well known in the art.

I claim as my invention:

1. An agitator adapted to have a vitreous coating fused thereon, comprising a body having a hollow hub portion and separately formed tubular blades closed at their outer ends and having their inner ends shaped to conform with the contour of said hub portion and united therewith over spaced openings formed therein and a sleeve on the hub portion for attachment to a shaft affording an external opening in communication with all portions of the interior for equalizing temperature and pressure conditions during the fusing of said coating thereon.

2. A rotary agitator comprising a tubular metal hub open at one end for the reception of a shaft and closed at the other with lateral openings spaced about its periphery, a plurality of blades each formed from a metal tube having an end welded to said hub over one of said lateral openings with its

outwardly extending portion elongated 55 transversely of and curved in the plane of rotation and closed by welding at the outer end, the interior portions of said blades and hub being in communication with the exterior through said shaft opening, and a 60 fused enamel coating protecting the agitator exterior.

3. In a rotary agitator, the combination of a hub portion comprising a length of metal tubing open at one end for the reception of a shaft and closed at the other end, and a plurality of separately formed blades spaced about the periphery of the hub each comprising a length of metal tubing having an end thereof welded to said hub with its 70 outwardly extending portion elongated transversely of and curved in the plane of rotation and closed at the outer end.

4. A centrifugal agitator adapted to have a vitreous coating fused thereon comprising a tubular body member including an end portion adapted for connection with a drive shaft and having an opposite closed end portion provided with a series of radially disposed openings and separately formed tubular blades having flattened portions sealed at their outer ends and circular end portions connected with the tubular body member around said openings and joined thereto by welding in a manner to form a one piece construction embodying a sealed enclosure permitting equalization of the temperature and pressure conditions during the fusing of said coating thereon.

5. A rotary agitator, comprising a blade 90 formed of a single piece of metal tubing and a hollow tubular hub member provided with an aperture on its periphery, said blade and hub member being welded together around said aperture, whereby the material 95 at the welded joint will be of substantially the same thickness as the material in the hub and blade members, said blade member being circular in cross section for a portion of the distance from the welded joint, the 100 remainder of the length of the blade member being flattened transversely of the plane of rotation of the blade and curved substantially spirally in the plane of rotation of the blade, the outer end of said blade 105 member being closed.

EDGAR B. NICHOLS.
